C. SHAW.
SANITARY COVER FOR CONTAINERS.
APPLICATION FILED JUNE 27, 1917.

Patented Dec. 3, 1918.

Inventor
CHARLES SHAW

By *Watson E. Coleman*

Attorney

UNITED STATES PATENT OFFICE.

CHARLES SHAW, OF COUDERSPORT, PENNSYLVANIA.

SANITARY COVER FOR CONTAINERS.

1,286,808.

Specification of Letters Patent.

Patented Dec. 3, 1918.

Application filed June 27, 1917. Serial No. 177,318.

To all whom it may concern:

Be it known that I, CHARLES SHAW, a citizen of the United States, residing at Coudersport, in the county of Potter and State of Pennsylvania, have invented certain new and useful Improvements in Sanitary Covers for Containers, of which the following is a specification, reference being had to the accompanying drawings.

10 This invention relates to certain new and useful improvements in means for closing or sealing cans or other containers for milk or the like, and the invention has for its primary object a very practical and efficient construction of device of this character which will be very sanitary in use and prevent the milk or other liquid from being contaminated in any way.

20 A further object of the invention is a device of this character embodying very few parts that may be very cheaply manufactured and easily applied or removed and not liable to get out of order and which may be very easily withdrawn whenever it is desired 25 to pour out the whole or part of the contents of the can or container.

30 A still further object of the invention is a sanitary cover of this character embodying a disk of pasteboard or fiber treated with oil, paraffin or other substance to make it impervious to the liquid, in combination with a sheet of preferably oiled paper that is designed to extend around the disk, and a spring clamping ring for holding the parts 35 in place, the sheet of paper above mentioned effectively separating the contents of the can or container from the disk and the spring and thereby assisting in maintaining the sanitary condition of the contents.

40 With these and other objects in view, as will more fully appear as the description proceeds, the invention consists in certain constructions, arrangements and combinations of the parts that I shall hereinafter 45 fully describe and claim.

For a full understanding of the invention, reference is to be had to the following description and accompanying drawing, in which—

50 Figure 1 is a vertical sectional view of a milk can embodying the improvements of my invention,

Fig. 2 is a horizontal section on the line 2—2 of Fig. 1, and

Fig. 3 is a detail view of the disk employed.

Corresponding and like parts are referred to in the following description and designated in all of the views of the accompanying drawing by like reference characters.

Referring to the drawing, the numeral 1 designates the body portion of a milk can of conventional form except as hereinafter specified, it being understood that this is merely selected for the purposes of illustration, and that the invention is applicable for use in connection with other cans or containers generally. 2 designates the neck of the can and 3 the usual or conventional outwardly flared mouth thereof.

In carrying out my invention, the neck 2 is formed with an interior groove 4 preferably rolled therein, and this groove is designed to receive a disk 5 snugly fitting therein and preferably formed of pasteboard or fiber treated with paraffin, oil or the like. In conjunction with the disk 5 I preferably use a protective sheet 6 preferably composed of oiled paper and of rectangular or other shape, said sheet being larger than the disk and extending over the entire lower face of the latter and upward around the edge or margin thereof, as clearly illustrated in the drawing.

In order to retain the disk and sheet in place I employ a split clamping ring 7 which is designed by its own inherent construction to spring out and hold itself within the groove 4 above the disk 5, and within the upwardly extending portions of the sheet 6, the clamping ring holding the parts securely in place as against accidental detachment, although it is so formed that it may be very easily detached and the cover thereby removed whenever it is desired to unseal the container and pour out any part of the contents thereof.

One end of the ring is returned inwardly upon itself in a circumferential direction as indicated at 8, and terminates in a substantially radial and inwardly projecting finger piece 9, and the other end of the ring projects inwardly in a radial direction to produce a complementary finger piece 10. It will,

therefore, be understood that by grasping these two finger pieces, and drawing them together, one end will overlap the other so that the ring will be contracted, and may

5 thus be readily inserted in place, and when released the ring will spring out and hold itself in position as well as the disk 5 and sheet 6 hereinbefore referred to.

From the foregoing description in connection with the accompanying drawing, the 10 operation of my improved sanitary cover for milk cans or other containers will be apparent. In the practical use of the device, after the disk 5 is inserted through the mouth 3 into the groove 4 of the neck 2 of the can with the protective sheet 6 extending over 15 the lower face of the disk and upward within the neck as best shown in Fig. 1, the clamping ring 7 is grasped and contracted and inserted in place and as soon as it is released it will expand into its normal shape and within the groove 4 and thereby hold 20 the other parts, as well as itself, securely in position. It is to be particularly noted (see Fig. 2), that in the applied position of the ring 7, it assumes a closed or unbroken formation with the ends abutting one against the other. Hence, no space is left where the 25 ends terminate, and the ring constitutes a

binder all the way around, and effectually precludes the possibility of leakage.

I claim:

The combination with a container provided with an internal groove, of a sealing device insertible within said groove, and an 35 expansible split ring insertible in said groove above said sealing device, one end of said ring being returned inwardly upon itself in a circumferential direction and having its extremity turned inwardly in a radial direction 40 to form a finger piece, and the other end of said ring being turned inwardly in a radial direction to form a complementary finger piece, the adjoining bends constituting the ends of the ring and abutting in the expanded condition of the ring when placed 45 within the groove, for the purpose specified, and the two inwardly projecting finger pieces being designed to be grasped whereby one end of the ring may overlap the other 50 and the ring contracted for insertion within or extraction from the groove.

In testimony whereof I hereunto affix my signature in the presence of two witnesses.

CHARLES SHAW.
